TRAVELLING BAG

Jack Barber, Waban, Mass.

Application June 13, 1956, Serial No. 41,889

Term of patent 14 years

(Cl. D87—5)

Figure 1 is a perspective view in closed position of a travelling bag showing my new design;

The dash-dash lines indicate stitching.

The dash-dot lines in Figure 2 indicate that the zipper is continuous as shown.

I claim:

The ornamental design for a travelling bag, as shown and described.
